(57) **CLAIM**

The ornamental design for a paint tray, as shown and described.

DESCRIPTION

FIG. 1 is a top front perspective view of a paint tray showing my new design;

FIG. 2 is a top view thereof;

FIG. 3 is a bottom view thereof;

FIG. 4 is a front view thereof;

FIG. 5 is a rear view thereof;

FIG. 6 is a left side view thereof;

FIG. 7 is a right side view thereof.

FIG. 8 top front perspective view of a paint tray, in an example environmental use, attached to the top of a paint container; and,

FIG. 9 is a right side view thereof.

The broken line showing is included for the purpose of illustrating unclaimed subject matter and forms no part of the claimed design.

The paint tray may be used with a paint container, as depicted in FIGS. 8 and 9. The paint container is an example environmental use for the paint tray and is not part of the claimed design sought to be patented.
